UNITED STATES PATENT OFFICE.

ELMER R. CORWIN, OF CHICAGO, ILLINOIS, ASSIGNOR TO CORWIN TELEPHONE MANUFACTURING CO., OF CHICAGO, ILLINOIS, A CORPORATION OF ILLINOIS.

TELEPHONE SYSTEM.

No. 901,785.

Specification of Letters Patent.

Patented Oct. 20, 1908.

Application filed December 26, 1906. Serial No. 349,374.

To all whom it may concern:

Be it known that I, ELMER R. CORWIN, citizen of the United States, residing at Chicago, in the county of Cook and State of Illinois, have invented a certain new and useful Improvement in Telephone Systems; of which the following is a full, clear, concise, and exact description, reference being had to the accompanying drawings, forming a part of this specification.

I will explain my invention by reference to the accompanying drawing and will also set it forth in the claims.

In the drawing is shown a telephone exchange system equipped in accordance with my invention.

There are indicated two of many sub-stations, A, B, each, in the embodiment of the invention shown, having a transmitter 1, a receiver 2, a call bell 3, a switch-hook 4, a condenser 5, an impedance coil 6, together with suitable contacts and circuit connections whereby, when the telephone receivers 2 are upon their switch-hooks, the bells 3, together with the condensers 5, are bridged across the sides of the telephone lines 7, 8, and whereby, when the telephone receivers are removed from their hooks, the bridges including said signal bells are opened and the transmitters are thrown into conductive connection with the lines, whereby battery may be fed therethrough through the impedance coil 6, and whereby telephone currents may be impressed upon the lines at the sub-stations at the transmitters or may be received at the receivers. I do not wish to be limited to the precise sub-station circuits indicated. The limbs 7, 8 of the telephone lines are connected with sleeve contacts or thimbles 9 and 40 tip springs or contacts 10, respectively. The contacts 10 are normally in connection with back contacts, each back contact constituting a terminal of a grounded conductor that includes the line lamp or signal device 12. 45 Each spring-jack includes another line spring 13 in permanent electrical connection with the corresponding sleeve 9 and normally in connection with a back contact that is grounded through a battery 14 common to the back contacts of the springs 13.

When a call is initiated, circuit is established through the line lamp 12 that may be traced from the grounded battery 14, through the spring 13 and its back contact, the line 55 limb 7, the impedance winding 6, the tele-

phone receiver and transmitter, the line conductor 8, the spring contact 10, the back contact of said element 10, the line signal device 12, to ground.

The operator's cord circuit is equipped with two plugs, which, in the preferred embodiment of the invention, are usable interchangeably as answering and connecting plugs, and which, as shown, are provided each with a tip adapted to make contact with the tip spring 10 and two sleeve contacts, one sleeve contact 15 constituting a terminal of the sleeve talking strand 16 of the cord circuit, while the other sleeve contact constitutes a terminal of a conductor including 70 a supervisory or clearing-out signal device 17, which is normally connected to ground when the armature of the associated supervisory relay 18 is unattracted.

When the operator answers a call, she inserts one of the plugs into the jack of the calling subscriber, and thereby connects the supervisory signal device 17 corresponding with the calling subscriber's line, with the battery 14. Since the sleeve contacts of the 80 inserted plug are adapted to engage the elements 9 and 13 of the occupied jack, and as the elements 9 and 13 are permanently connected electrically, the supervisory device 17 is connected with the battery 14, as stated. 85 The supervisory signal controlling devices 18 are included in bridge of the talking strands of the cord circuit, so that when the telephone receivers are removed from the switch-hooks at the subscribers' stations, said 90 signal controlling devices or relays 18 are included in conductively continuous paths established by reason of the impedance coils 6 and their connections, thereby then preventing the presentation of supervisory signals. When, however, a subscriber restores his telephone upon its hook, the conductively continuous path afforded at his station by the impedance coil 6 and the connections thereof, is replaced by the signal bell branch 100 including the condenser 5, so that the corresponding relay 18 is included in open circuit, whereby its armature is allowed to fall back and the corresponding supervisory signal device 17 is included in a closed circuit, 105 traced hitherto, and including the sleeves of the corresponding plug and the contact elements 9 and 13 of the engaged jack.

Assuming that the system is equipped with double supervision, as illustrated, the 110

- operator, upon seeing both signals occasioned by two connected subscribers when they restore their telephones, withdraws the plugs from the jacks of said subscribers, and there-
 5 by opens the circuits of the signal devices 17, for the withdrawal of the plugs causes electrical disconnection between the sleeves thereof.
- By "sub-station" I, of course, do not limit
 10 myself to a subscriber's telephone sub-sta-
 tion, since it is obvious that the invention
 resides in effecting control of the relay over
 a telephone line, whether or not said tele-
 phone line extends to a subscriber's outfit.
- 15 The cord circuit herein illustrated is de-
 sirable symmetrical; that is, either plug may
 be used as an answering plug or a connect-
 ing plug, and in connection with this
 20 characteristic, I provide apparatus for au-
 tomatically determining the relations of
 the operator's telephone equipment with the
 cord circuit, so that no matter which plug
 25 is used by the operator as an answering plug,
 the operator may have automatic connection
 of her telephone conductors effected with a
 calling telephone line, which connection is
 broken when the operator has connected two
 30 lines together. To this end, I desirably em-
 ploy the instrumentalities illustrated.
- I have shown condensers 19, 20 and 21,
 35 which, as it will appear by inspection of the
 diagram, cause separation between the cir-
 cuits of the relays 18 and the relays 22,
 which latter relays take part in the control
 40 of the association of the operator's telephone
 equipment with the cord circuit. Each re-
 lay 22 is included in the same circuit with
 the associate signal device 17, so that when-
 ever said signal device 17 is in circuit, the
 45 corresponding relay 22 is in circuit and is
 energized, whereby the cord circuit is not
 rendered more complicated to secure the re-
 sults of my invention. The relays 22 are
 also in the same bridges with the relays 18,
 50 so that the relay 22 corresponding to the
 plug used as an answering plug, is sure to
 be energized to attract its armature and dis-
 connect the armature-switches 23, 24 from
 their contacts, said contacts 23, 24 constitut-
 55 ing terminals of tap conductors or legs
 branched from the talking strands of the
 cord circuit, the armature-switches 23, 24
 constituting terminals of the operator's tele-
 phone equipment 25. As appears, there are
 60 two sets of switches 23, 24 with their asso-
 ciate contacts, one set being controlled by
 the relay 22 corresponding with an answer-
 ing plug and the other set being controlled
 by the relay 22 corresponding with the plug
 65 used as a connecting plug, and though con-
 tact is broken at 23, 24 by reason of the
 energization of the relay 22 corresponding
 to the plug used as an answering plug, con-
 tact is not yet broken at 23, 24 respecting the
 70 companion relay 22, so that the operator is

at once brought into communication with
 the calling party, the subscriber or other
 party, by reason of the contact maintained
 at the contacts 23, 24 associated with the
 plug then used as a connecting plug. The
 75 contacts 23, 24 of one set are multiply re-
 lated with the contacts 23, 24 of the other
 set; that is, the operator's telephone equip-
 ment has two sets of terminals multiply re-
 lated, each set including a pair of contacts
 23, 24.

When the plug used as a connecting plug
 is inserted in the jack of the called sub-
 scriber, a local circuit is established for the
 associate relay 22, which may be traced from
 80 the grounded battery 14, through the said
 relay 22 in question, the sleeves of the plug
 used as a connecting plug now electrically
 connected, the associate supervisory lamp 17,
 to ground, whereby the operator's telephone
 85 set is automatically excluded from connec-
 tion with the cord circuit.

It will be seen that the control of the
 operator's telephone outfit herein described,
 is had whether either plug is used as an
 90 answering plug or a connecting plug.

It will be seen that the plugs coöperate
 with the jacks in establishing local circuits
 for the relays 22, and that these circuits are
 initially local at the connecting end of the
 95 cord circuit and are thereafter maintained
 over the line when the called subscriber re-
 sponds, for then the local circuit is opened
 at the contact of the associate called sub-
 scriber's supervisory relay 18.

100 It will be noted that the called subscriber
 has no control over the relay 22 associated
 with his line, to the extent of changing the
 operated condition of said relay, but that
 such control is exercised only at the exchange
 105 by a calling plug and the engaged jack.

While I have herein shown and particu-
 larly described the preferred embodiment of
 my invention, I do not wish to be limited to
 the precise embodiment herein set forth, but,
 110

Having thus described my invention, I
 claim as new and desire to secure by Letters-
 Patent the following:—

1. A telephone exchange system including
 telephone lines, jacks therefor, a cord circuit
 for uniting telephone lines in conversation,
 an operator's telephone equipment having
 multiplied terminals, and two relays, one
 serving to control the connection of one set
 of said multiple terminals with the cord cir-
 115 circuit and the other serving to control the
 connection of the other set of said multiple ter-
 minals with the cord circuit, one of said
 relays being controlled by the plug used as
 an answering plug and apparatus associated
 120 with the line connected with the said answer-
 ing plug, while the other relay is controlled
 by the plug used as a connecting plug and
 apparatus associated with the line connected
 125 with the said connecting plug.

130

2. A telephone exchange system including telephone lines, jacks therefor, a cord circuit for uniting telephone lines in conversation, an operator's telephone equipment, and two 5 relays, each serving to establish connection of the operator's equipment with the cord circuit, and each adapted to break the connection it effects, one of said relays being controlled by the plug used as an answering 10 plug and apparatus associated with the line connected with the said answering plug, while the other relay is controlled by the plug used as a connecting plug and apparatus associated with the line connected with the 15 said connecting plug.
3. A telephone exchange system including telephone lines, jacks therefor, a cord circuit for uniting telephone lines in conversation, an operator's telephone equipment having 20 multiplied terminals, and two relays, one serving to control the connection of one set of said multiple terminals with the cord circuit and the other serving to control the connection of the other set of said multiple terminals with the cord circuit, one of said 25 relays being controlled by the plug used as an answering plug and apparatus associated with the line connected with the said answering plug, while the other relay is controlled 30 by the plug used as a connecting plug and apparatus associated with the line connected with the said connecting plug, the relay associated with the plug used as an answering
- plug serving to break the connection it effects, while the relay associated with the 35 plug used as a connecting plug maintains the connection it governs until said connecting plug has been connected with the called line.
4. A telephone exchange system including telephone lines, jacks therefor, a cord circuit 40 for uniting telephone lines in conversation, an operator's telephone equipment, and two relays, each serving to establish connection of the operator's equipment with the cord circuit, and each adapted to break the connection it effects, one of said relays being controlled by the plug used as an answering plug and apparatus associated with the line connected with the said answering plug, while the other relay is controlled by the plug used 45 as a connecting plug and apparatus associated with the line connected with the said connecting plug, the relay associated with the plug used as an answering plug serving to break the connection it effects, while the 50 relay associated with the plug used as a connecting plug maintains the connection it governs until said connecting plug has been connected with the called line.

In witness whereof, I hereunto subscribe 60 my name this 22nd day of December A. D., 1906.

ELMER R. CORWIN.
